UNITED STATES PATENT OFFICE.

HIRAM STEVENS MAXIM AND ARTHUR TREVOR DAWSON, OF LONDON, ENGLAND, ASSIGNORS TO THE VICKERS, SONS & MAXIM, LIMITED, OF SAME PLACE.

GAS-CHECK FOR PROJECTILES.

SPECIFICATION forming part of Letters Patent No. 628,106, dated July 4, 1899.

Application filed August 24, 1898. Serial No. 689,377. (No model.)

To all whom it may concern:

Be it known that we, HIRAM STEVENS MAXIM, a citizen of the United States, Chevalier of the Legion of Honor and civil and mechanical engineer, and ARTHUR TREVOR DAWSON, a subject of the Queen of Great Britain, late of the Royal Navy, both residing at 28 Victoria street, London, England, have invented certain new and useful Improvements in Gas-
10 Checks for Projectiles, of which the following is a specification.

It has heretofore been usual to provide projectiles with means for preventing or diminishing the erosive effects of the explosive upon the bore of a gun when heavy charges are used therein. In some cases it has been customary to equip the projectile with a cap or disk so arranged in combination with a plastic ring or gas-check that at the moment of the discharge of the gun the gas-check will be subjected to greater pressure per square inch of its area than that existing in the gun at the rear of the projectile.

The object of our present invention is to produce a gas-check or ring of this character especially designed for the projectiles of heavy guns, which, while sufficiently plastic to adapt itself to the bore of the gun, will have greater stability and will be capable of resisting a greater shearing stress than the rings formed of wax, plumbago, and asbestos heretofore used.

In order that our improvement may be clearly understood and readily carried into effect, we shall describe the same with reference to the accompanying four figures of drawings, which are sectional views showing the improved gas-check in its preferred and modified forms and illustrating the manner of applying it to different forms of projectile.

Figure 1 illustrates the whole of the rear portion of a projectile provided with our improved gas-check; but the remaining figures show only so much of the rear end of the projectile, the annular base-piece, and the plastic ring as is necessary for a proper comprehension of the manner in which our invention is or may be utilized or applied.

In all the figures, A is the projectile, and a

the boss at the base thereof. B is the annular base-piece or collar, C the plastic ring or gas-check, and D the driving-band.

Referring more particularly to Fig. 1, the periphery of the boss a is screw-threaded to receive the corresponding screw-threaded portion b of the annular piece or collar B, the direction of the screw-threads being opposite to that of the rifling of the gun. The said annular piece or collar B is dished at b' to impart elasticity to said collar and to form the forwardly-projecting peripheral portion or flange b², which lies directly in contact with the plastic ring C. This ring is constructed of copper wires c, embedded in asbestos saturated with wax and plumbago and afterward compressed and coated or covered with metal. The diameter of the projectile is diminished at a', so that the flange b² of the annular piece B, although not greater in diameter than the driving-band D, can act upon the plastic ring C. In some cases, however, the diameter of the said annular piece B may be large enough to engage with the rifling of the gun. The plastic ring C is formed with a shoulder c' to fit the corresponding shoulder formed by diminishing the diameter of the projectile at a', such shoulder effectually preventing the plastic ring from shifting forwardly when acted upon by the flange of the annular piece B. We prefer to construct the driving-band as shown at d, so as to prevent the entrance of the projectile too far into the gun in cases where the bore is too loose—for example, when it has been enlarged by erosion.

The plastic ring is in the above-described construction unprovided with the metallic coating or covering; but in Figs. 2, 3, and 4 such coating or covering is shown on the ring. In Fig. 2 it consists of numerous convolutions of thin wire c², wound around the circumference of the ring. In Figs. 3 and 4 it consists of a casing c², inclosing the said ring on its exposed surfaces. In these examples the metallic coating or covering may be applied to the ring by electrodeposition, or a thin casing of sheet metal of the proper shape and dimensions may be made and be applied to the said ring in any appropriate manner. The plastic

ring is in Fig. 4 made wider than that shown in the previous figures, so as to overlap the rear portion of the band D. In other respects the construction of the parts shown in Figs. 5 2, 3, and 4 is similar to that illustrated in Fig. 1.

In the foregoing constructions the pressure of gas acting behind the annular piece B has to crush or deform the latter before the plastic ring C can be compressed sufficiently to force it radially outward against the bore of the gun.

Having now described our invention, what we claim is—

1. The gas-check for projectiles herein described, consisting of a ring composed of wire coils or rings embedded in a mass of plastic material compacted and molded to the proper form under pressure.

2. The gas-check for projectiles herein de-

scribed consisting of a plastic ring composed 20 of wire coils or rings embedded in a compacted mass of asbestos saturated with a mixture of wax and plumbago.

3. The gas-check for projectiles herein described consisting of a ring composed of wire 25 coils or rings embedded in a mass of plastic material, compacted and molded to the proper form under pressure and coated or covered with a metal such as copper.

In testimony whereof we have hereunto set 30 our hands, in presence of two subscribing witnesses, this 29th day of July, 1898,

HIRAM STEVENS MAXIM.
ARTHUR TREVOR DAWSON.
